CARTON

John Allan, Morris, Ill., assignor to Self-Locking Carton Co., Chicago, Ill., a corporation of Illinois

Application December 27, 1932, Serial No. 648,838

2 Claims. (Cl. 229—29)

The present invention relates to cellular cartons and has particular reference to an improvement in cartons of the type adapted to form a carrier for eggs or similar fragile articles.

5 Cartons of the cellular type are largely used for transporting eggs and the like, and in such use the cartons are often subjected to jarring or to similar shocks which have a tendency to cause breakage of the eggs. It has been suggested to provide the bottom of egg cartons with cushioning means, and it is standard practice to form the bottom of the carton in the shape of an inverted V, whereby the egg is suspended above a surface upon which the carton is placed.

10 15 The present invention pertains to improvements in cartons of this general type and has a principal object in the provision of a flat bottom carton having an inner bottom section of inverted V-shape.

20 An additional object is to provide a carton having an inner or false bottom of greater width than the outer bottom and formed of the same piece of material as the main body of the carton.

25 A further object is the provision of improved means for interlocking a longitudinal partition with a bottom section.

These and other objects will be apparent from a consideration of the following illustrative and 30 explanatory description and by reference to the accompanying drawing, in which

Fig. 1 is a top view of a carton constructed in accordance with my invention and having its cover in opened position;

35 Fig. 2 is a cross sectional view of the carton shown in Fig. 1 taken along line 2—2, the cover of the carton being in closed position;

Fig. 3 is a cross sectional view taken along line 3—3 of Fig. 1; and

40 Fig. 4 is a plan view of the blank from which the carton shown in Fig. 1 is constructed.

The carton shown in the drawing is made from a blank of paper or other suitable material cut and scored to form in the order named 45 a cover-locking strip 1, a top 2, an outer rear wall 3, a flat outer bottom section 4, a front wall 5, cross partitions 6 and inner rear walls 7 and an inner or false bottom section 8 of greater width than the outer bottom section and being 50 scored along its central portion. The cut and scored blank is folded over and the inner wall 7 is adhesively secured to the outer rear wall 3 so that the cross partitions 6 lie in a substantially horizontal plane when the carton is erected.

55 Ed. In production, it is desirable to fold the

blank over along a scoring between the cross partitions 6 and the front wall 5 and to form a reverse fold along the scoring between the inner rear wall 7 and the inner bottom section 8. Glue is applied to the outer face of the inner rear wall 7 and the blank is folded over along the scoring between the rear wall 3 and the outer bottom section, thereby forming a collapsed or flattened carton. In this condition, the outer bottom section 4 and the wall 5 are in substantially a horizontal plane whereby the inner bottom section 8, which is wider than the outer bottom section, can extend beyond the latter to partially overlie the front wall 5.

To erect the carton, pressure is applied along 70 the scoring between the cross partitions and the front wall and along the scoring between the rear wall and the bottom section whereby the walls are distended into substantially rectangular cross section.

75 When the walls of the carton have been pressed into substantially rectangular cross section, or in other words, into erect position, a separate longitudinal partition 9 is pressed downwardly against the substantially horizontal cross partitions, thereby rotating the latter into vertical position. The cross partition is provided with a plurality of upwardly extending slots 10 which engage the cross partitions below the corresponding 11 thereon. This forms an interlock which maintains the cross partitions in substantially vertical or erect position. Between the adjacent slots 10 are provided a plurality of downwardly extending feet 12, each of which has a hook 13 pointing toward one end of the 80 longitudinal partition. These feet are adapted to be thrust through corresponding openings 14 which are arranged along the central portion of the false bottom 8. The feet extend into these openings as the longitudinal partition is thrust 85 downwardly against the cross partitions. When the longitudinal partition is extended into its final position in engagement with the cross partitions the feet 12 extend to the outer bottom section. The longitudinal partition is then 90 pushed in the direction toward which the hooks or shoulders 13 point, thereby engaging the latter with the underside of the false bottom adjacent the openings 14 therein. This forms an interlock which prevents the longitudinal partition from being removed by upward movement.

100 The false bottom is free to move within the body of the carton and in accordance with my invention the outer bottom section is provided with openings 16, whereby the fingers of the op- 110

erator may be thrust upwardly through the bottom and into contact with the false bottom, whereby the position of the latter when the longitudinal partition is thrust downwardly thereagainst may be controlled to some extent.

5 It has been found in practice that by pressing the false bottom upwardly during the insertion of the longitudinal partition the latter operation is considerably facilitated.

10 An objection to the use of longitudinal partitions of this type in cartons known heretofore is that after insertion the longitudinal partitions are apt to be accidentally withdrawn by movement of the longitudinal partition in the 15 direction opposite that toward which the hooks 13 point. As shown in the drawing, I provide a downward extension 17 on the end of the longitudinal partition toward which the shoulders 13 point and this extension engages a slot 18 in 20 the false bottom. It will be seen that engagement of this projection with the false bottom will prevent or retard retraction of the longitudinal partitions.

25 Cartons constructed in accordance with the above described embodiment of my invention offer substantial protection to fragile articles packed therein. The false bottom is wider than the outer bottom of the carton and has its outer ends pressed against the front and rear 30 walls. It is also suspended by means of the hooks on the longitudinal partition. This construction prevents the eggs from contacting the

surface upon which the carton is positioned and eggs packed in this type of carton may be dropped from a considerable height without the percentage of breakage which is characteristic of cartons known heretofore.

80 Various changes in the above described embodiment of my invention will occur to those skilled in the art and such modifications as come within the spirit of my invention are intended to be included in the appended claims.

85 I claim:

1. A carton of the type described, comprising a single blank cut, scored and folded to form front and rear walls, a flat bottom section, cross partitions, an inner wall section, and an inner bottom section of greater width than the width of said first named bottom section, said bottom section being folded upwardly in its central portion and suspended to a longitudinal partition.

90 2. A carton of the type described, comprising front and rear walls, a bottom section, transverse partitions, an inner bottom section folded upwardly along its central portion in inverted V-shape, and a longitudinal partition engaging 100 said cross partitions to maintain the same in erect position, said longitudinal partition having feet extending through openings in said inner bottom section and shoulders engaging the under surface of said bottom section to maintain the same in suspended condition.
